UNITED STATES PATENT OFFICE.

SAMUEL W. RUSHMORE, OF PLAINFIELD, NEW JERSEY.

GAS-PRODUCER.

No. 891,292.

Specification of Letters Patent.

Patented June 23, 1908.

Application filed May 19, 1905. Serial No. 261,225.

To all whom it may concern:

Be it known that I, SAMUEL W. RUSHMORE, a citizen of the United States, residing at Plainfield, in the county of Union and State 5 of New Jersey, have invented certain new and useful Improvements in Gas-Producers; and I do hereby declare the following to be a full, clear, and exact description of the invention, such as will enable others skilled in the 10 art to which it appertains to make and use the same.

My invention relates to gas producers and is intended particularly for use with the so-called suction producers to insure practically 15 uniform combustion of the fuel in the chamber and to provide a convenient means for supporting the fuel therein so that the waste can be removed easily.

The essential features thereof are the producer of the well known type, having a vertically arranged producing, or fuel, chamber, inclosed within a cylindrical shell, provided with a fire-brick lining, and having an upper opening for the fuel supply and a bottom 25 opening for the air supply. Below such bottom opening for the support of the fuel in the chamber I arrange a grate at a short distance from the lower wall of the chamber, leaving a space between the grate and the wall which 30 is small, but sufficiently large, to remove the larger particles of ash, clinker, waste, etc., which will not readily pass through the grate. I also arrange immediately around said bottom opening means for varying the size 35 thereof; for the purpose hereinafter more fully described. Such means may desirably consist of a metallic ring composed of segmental plates fitted to slide-ways formed in the bottom of the wall and provided with 40 means by which said plates simultaneously, or independently, may be moved inwardly and outwardly to diminish, or increase, the size of said opening.

In the drawing herewith, I have shown a 45 desirable embodiment of my invention which, however, may be varied in form, construction and arrangement of parts without departing from the spirit of my invention.

Figure 1 is a vertical section of a producer 50 of a common type provided with my invention. Fig. 2 is a plan showing the arrangement and mode of operation of the segmental plates. Figs. 3, 4 and 5 are, respectively, plan, end elevation and side elevation of a 55 detached plate.

In the figures, 1 indicates the metallic, cy-

lindrical shell provided with the fire-brick lining 2, supported on the annular plate 3, secured by any suitable means within the metallic shell, and inclosing the producing 60 chamber 20, having an outlet pipe 21 for the gas, and metallic top-plate 22, provided with a fuel opening 23, and supporting a hopper 24 for the fuel supply, which may be closed by balance-cover 25, having a suitable locking means 26. The fuel opening 23 may be closed by a suitable valve 27, carried on a journaled arm 28 provided with an adjustable counterbalance weight 29. The bottom 65 of the producing chamber may be gradually contracted, as here shown, and provided with a suitable opening 30, commonly and preferably made circular.

Immediately below the bottom opening is arranged the grate 5, which I arrange a short 75 distance below the bottom wall of the chamber so as to leave a small space 4 between it and said bottom wall, which is merely large enough to permit easy removal of the clinker and other larger particles, as aforesaid, which 80 will not readily pass between the grate bars.

Immediately below annular plate 3 is arranged a corresponding annular plate 7, also suitably secured in the shell and having a corresponding circular opening. Said annular plates 3 and 7, being arranged parallel and at a short distance one below the other, provide an annular bearing or slide-way in which is arranged a sectional ring adapted to be moved so as to diminish the size of the opening 30. This sectional ring may desirably 85 be composed of independent, metallic, segmental plates 6, supported and moving in the slide-way, and provided with outwardly extending, threaded bolts or shanks 9, to 90 each of which is fitted an external hand-wheel 8, provided with a circular flange 10, fitting in bearing 11 on the shell. By turning each hand-wheel, its segmental plate is 95 adjusted inwardly or outwardly, to vary the size of the central bottom opening. The front edges of the plates may be beveled, or, as here shown, more or less of their radial edges beveled, so that when being moved inwardly they more easily force their way, or 100 cut through the bed of ash and fuel. These sections may evidently be arranged to be moved simultaneously, if desired.

It will be understood that my sectional ring for varying the size of the opening and 110 my peculiarly arranged grate are desirably used in the same producer, but the grate may

be used by itself, or, if desired, the adjusting ring may be used without the grate and the weight of the fuel bed supported upon the mass of ashes, as in producers to which the air and steam are supplied to the fuel bed under pressure.

It has been found in practice that with producers constructed in the usual way, as shown in Fig. 1 with the opening at the bottom of the fuel bed of the full diameter of the lower portion of the brickwork, it is difficult or impossible to obtain a uniform rate of combustion, as the air, entering at the bottom, finds an easier path by entering at a point near the lower edge of the brick work, than by passing through the mass of ash and clinker upon the grate; with the result that the fuel is consumed at a much more rapid rate in the immediate vicinity of the brick walls than at the center of the mass, so that after the producer has been in operation for a time, there accumulates upon, or next to the brick walls a layer of ash and clinker, which, being very porous, permits the air to pass around the heated fuel at the center and to cause combustion of the gas formed at the center of the bed, resulting not only in a great waste of fuel but seriously reducing the heating value of the gas.

I overcome the difficulties described due to the entrance of the air near the brick work, by providing the movable segments 6, so that when the segments are all brought together, the air can enter only through the central passage remaining at the center, around which it is equally distributed through the fuel bed. During the normal operation of the producer, the segments are left in their inward position, and much of the ash and clinker is removed from time to time through the restricted central opening. At intervals, however, the segments are withdrawn one at a time (or simultaneously) by means of the hand-wheels, to permit the complete removal of ash and clinker which may have formed directly above them. I thus overcome all the difficulties due to the unequal distribution of air through the fuel bed and yet retain all of the advantages of the large unrestricted opening for the removal of ash and clinker. I am aware that producers have been built with openings at the bottom having an area smaller than the lowest diameter of the brick work, but know of no one who has provided a variable opening.

Having thus described my invention, what

I claim as new and desire to secure by Letters Patent, is:—

1. In a gas producer having a vertically arranged chamber provided with an opening in its bottom, the combination with a grate arranged below said opening, of a ring of segmental plates arranged above said grate, and means to adjust said plates in and out, to vary the size of the opening.

2. In a gas producer having a vertically arranged chamber provided with an upper opening for the fuel supply and a circular opening in its bottom, the combination with a grate arranged below said bottom opening and a short distance below the bottom of the chamber to support the fuel, of a ring composed of separate segmental plates arranged to move horizontally in suitable supports, and means independently to adjust said plates in and out to diminish or increase the size of the circular opening.

3. In a gas producer having a cylindrical metallic shell lined with fire-brick inclosing a producing chamber, provided with an upper fuel opening, with the lower portion of its walls inwardly inclined, and with a central, circular, bottom opening, of a grate arranged a short distance below said bottom opening, two parallel, annular plates arranged around the bottom opening to form an annular slide-way, and movable pieces arranged in said slide-way, and adapted to be moved in and out to vary the size of the central opening, substantially as described and shown.

4. In a gas producer having an opening in the bottom of the chamber, imperforate plates to vary the size of the opening and means to operate said plates in one plane.

5. In a gas producer having an opening in the bottom of the chamber, a series of horizontally arranged plates to vary the size of the opening and means to move said plates radially in the horizontal plane.

6. In a gas producer having a vertically arranged chamber provided with a bottom opening, a grate arranged below said opening, imperforate plates arranged permanently above the grate, and means to operate said plates to vary the size of the opening.

In testimony whereof I affix my signature in presence of two witnesses.

SAMUEL W. RUSHMORE.
